UNITED STATES PATENT OFFICE.

FRANCIS KERNAN, JR., OF UTICA, AND WILLIAM H. LANDERS, OF SYRACUSE,
ASSIGNORS TO THE KERNAN FURNACE COMPANY, OF UTICA, NEW YORK.

DESIGN FOR A FURNACE.

SPECIFICATION forming part of Design No 20,648, dated March 31, 1891.

Application filed January 14, 1891. Serial No. 377,770. Term of patent 14 years.

To all whom it may concern:

Be it known that we, FRANCIS KERNAN, Jr., and WILLIAM H. LANDERS, citizens of the United States, residing, respectively, at Utica, 5 in the county of Oneida and State of New York, and at Syracuse, in the county of Onondaga and State of New York, have invented a new and useful Design for Furnaces, of which the following is a specification.

10 Our design relates to the ornamentation of furnaces having a rectangular body and a laterally-bulging or overhanging kettle-casing, and which are commonly known as "agricultural furnaces."

15 The accompanying drawing represents a furnace embodying our new design.

The leading features of our design consist of transversely-corrugated corner columns and ribbed ornamentations of the flat side 20 walls.

A represents one of the side walls of the rectangular furnace-body, B the front wall, and C the convex or bulging kettle-casing.

D are columns or posts located at the corners 25 of the rectangular body. These columns are ornamented by transverse alternately wide and narrow rounded ribs or corrugations, which cover the columns from top to base.

E are upright ribs or projecting bars having rounded ends and arranged in relief on 30 the flat side walls A in the panel below the kettle-casing.

F represents the top plate, which has its projecting rim ornamented with a row *f* of convex ornamentations, which produce a 35 crimped effect. The rim of the bottom plate G is ornamented by a similar row *g* of crimped ornamentations.

An animal or other device may be outlined or otherwise represented upon the bulging 40 kettle-casing, as shown in the photograph; but such animal or device forms no essential part of this design.

We claim—

The design for an agricultural furnace here- 45 in shown and described.

Witness our hands this 2d day of January, 1891.

FRANCIS KERNAN, JR.
WILLIAM H. LANDERS.
